Primary Examiner — Patricia Palasik(74) *Attorney, Agent, or Firm* — Kelly & Kelley, LLP(57) **CLAIM**

The ornamental design for a roll-out wheel, as shown and described.

DESCRIPTION

FIG. 1 is a an elevated perspective view of the roll-out wheel;

FIG. 2 is a lowered perspective view of the roll-out wheel;

FIG. 3 is a left side view of the roll-out wheel;

FIG. 4 is a right side view of the roll-out wheel;

FIG. 5 is a top view of the roll-out wheel;

FIG. 6 is a bottom view of the roll-out wheel;

FIG. 7 is a front view of the roll-out wheel; and,

FIG. 8 is a back view of the roll-out wheel.

The broken lines in the drawings depict unclaimed environmental subject matter.
